UNITED STATES PATENT OFFICE.

GEORGE W. EYCLESHYMER, OF TROY, NEW YORK, ASSIGNOR OF ONE-HALF
TO MARY J. EYCLESHYMER, OF RAYMERTOWN, NEW YORK.

STEAM-RADIATOR.

SPECIFICATION forming part of Letters Patent No. 673,767, dated May 7, 1901.

Application filed April 10, 1900. Serial No. 12,349. (No model.)

To all whom it may concern:

Be it known that I, GEORGE W. EYCLESHYMER, of Troy, in the county of Rensselaer and State of New York, have invented certain new and useful Improvements in Steam-Radiators; and I hereby declare that the following is a full, clear, and exact description thereof, reference being had to the accompanying drawings, which form part of this specification.

10 This invention is an improvement in steam-radiators; and its objects are to produce a more uniform distribution of the steam or heating element to the pipes, to avoid sharp bends in the flow of the steam through the 15 apparatus, and to cause the steam and water of condensation to always flow downwardly.

The invention therefore consists in the novel construction and combination of parts hereinafter described and claimed, and illustrated in the accompanying drawings, in which—

Figure 1 is a vertical section through the apparatus. Fig. 2 is a horizontal section on line 2 2, Fig. 1, looking downward. Fig. 3 is 25 a detail vertical section on line 3 3, Fig. 1; and Fig. 4 is a sectional detail showing the connection of the pipe-sections, part of the intermediate section being shown in full lines.

The radiator is composed of upper and 30 lower headers A and B, connected by a series of vertical pipes C. The peculiar construction of the header A is one of the features of the present invention. This header A has a central upwardly-projecting enlargement E, which is connected to the steam-supply pipe S, and from this enlargement the top walls a of the header incline outwardly and downwardly toward the ends thereof. Within the header is a series of transverse 35 curved plates or partitions F, the upper parts of which converge within the enlargement E, and their lower parts extend downwardly and outwardly in the body of the header and diverge therein somewhat in fan shape, as 40 shown. These partitions F separate the steam entering the header and disperse the same therein, so that the supply of steam will be more uniformly distributed throughout the header and every pipe in the heater will receive a substantially similar supply of steam, 45 which will result in a much more uniform

heating of the pipes. The header B is provided with an inclined bottom b, through which the water of condensation is directed to the outlet-pipe O, which is tapped into one 55 end of the bottom, as shown.

As it is very inconvenient and troublesome to connect the headers A B by vertical or straight sections of pipe, I preferably make the pipes C in upper and lower sections C' 60 and C², respectively, the lower end of the upper section and the upper end of the lower section being respectively provided with couplings C³ and C⁴. These couplings are provided with right and left hand screw-threads, 65 and, as shown, they are connected by similarly threaded pipe-sections c, which are inclined at an angle of about forty-five degrees. Each section c consists of a straight pipe provided on its opposite ends with right and left 70 hand screw-threads, thus enabling the ends of said sections c to be screwed into the couplings C³ and C⁴, respectively, of the vertical sections C' and C², and as these sections C³ and C⁴ are curved at their centers on an angle of about forty-five degrees the sections c 75 when mounted in position in the apparatus will also be on angle of about forty-five degrees to the vertical sections C' and C², which, it will be observed, do not aline. By this 80 means any pipe can be easily removed for repairs and replaced when necessary, and sharp bends in the pipes C are entirely obviated.

Only one set of pipes C is shown in the drawings connecting the headers A B; but obviously the number of rows of these pipes may be multiplied, according to the size of the heater desired. Preferably when more than one row of pipes C is employed the pipes in adjoining rows alternate, so that air passing 85 between them through the radiator will 90 be directly subjected to the greatest amount of heating-surface.

It will be observed that as the steam enters the top header A and flows downwardly 95 through the pipes C it will assist in carrying any water of condensation into the header B and off through the pipe O, and owing to the absence of any sharp bends in the pipe the outflow of the steam or heating fluid and 100 of any water of condensation will be unobstructed.

The construction shown is well adapted for single radiators or for different sections of a radiator, as each header and base and its connected parts constitute a unit, and a number 5 of such units can be connected in series or multiple to form larger heaters, if desired.

When the apparatus is to be used for heating air for furnaces, the radiator may be inclosed in a casing in the ordinary manner, 10 through which casing the air is blown and is heated by external contact with the pipes.

Having thus described my invention, what I claim is—

1. The combination of an upper inlet-header 15 provided with a straight bottom wall, and a curved top wall, the top wall converging and curving upwardly into a central enlargement or boss and diverging and curving downwardly until it forms a junction with the lower 20 wall, and a series of curved deflecting-plates in said inlet-header conforming in contour to the shape of the said upper wall of the header; with a lower outlet-header provided with an inclined bottom and an outlet in the lower 25 end of said bottom, and a series of interposed connecting-pipes for said headers, for the purpose and substantially as described.

2. In a radiator, the combination of an inlet-header and an outlet-header; with upper 30 and lower series of straight vertically-disposed pipe-sections, the pipes of the upper series and those of the lower series being out of vertical alinement, and a coupling on the projecting end of each of said sections, one of 35 said couplings being provided with left-hand screw-threads and the other of said couplings with right-hand screw-threads, and intermediate straight sections of pipe connecting the upper and lower vertical sections, said connecting pipe-sections being also provided with 40 right and left hand screw-threads on their opposite ends, for the purpose of enabling the connecting-sections to screw into the respective couplings of the vertical sections, all 45 substantially as and for the purpose set forth.

3. The combination in a radiator of an upper header and a lower header, a series of curved deflecting-plates in said upper header and an inclined bottom for said lower header; 50 with series of vertical steam-conducting pipes connecting said headers, each of said pipes consisting of a long and a short straight section, the long section and the short section being always out of vertical alinement, and 55 each of said sections being provided on its projecting end with a curved coupling, screw-threaded on its free end, one of said couplings being provided with left-hand screw-threads and the other of said couplings with 60 right-hand screw-threads, and an intermediate straight section of pipe connecting the long and short vertical sections, said connecting pipe-section being also provided with 65 right and left hand screw-threads on its opposite ends for the purpose of enabling each connecting-section to screw into the respec-

tive couplings, the series of connecting-sections, in front elevation, being arranged on a line drawn diagonally from one side of the upper header to the opposite side of the lower 70 header, substantially as described.

4. In a radiator-heater, the combination of the upper header A having a central enlargement or boss E connected to the inlet-pipe, the top walls of said header being inclined 75 outwardly and downwardly from said enlargement to the bottom of the header, and a series of curved partitions or deflecting-plates F within said header converging within the enlargement and diverging within the body of 80 the header; with the lower header and the series of vertical sectional heating-pipes connecting the headers for the purpose and substantially as described, said pipes being formed of upper and lower straight sections, 85 the upper sections being always out of alinement with the lower sections and each section being provided on its projecting end with a coupling, screw-threaded on its free end, one of said couplings being provided with 90 left-hand screw-threads and the other of said couplings with right-hand screw-threads, and intermediate straight sections of pipe connecting the upper and lower vertical sections, said connecting pipe-sections being also provided with 95 right and left hand screw-threads on their opposite ends for the purpose of enabling the connecting-sections to screw into the respective couplings, substantially as described. 100

5. In a heater, the combination of the upper header A having a central enlargement E connected to the inlet-pipe and a series of curved deflecting-plates F within said header; and the lower header, provided with an inclined bottom; with a series of sectional heating-pipes connecting the headers, the said pipes being formed of upper and lower straight sections, the upper sections being always out of vertical alinement with the lower 105 sections and each section being provided on its projecting end with a curved coupling, one of said couplings being provided with left-hand screw-threads on its free end and the other of said couplings with right-hand 110 screw-threads on its free end, and intermediate straight sections of pipe connecting the upper and lower vertical sections, said connecting-sections being also provided with right and left hand screw-threads on their opposite ends for the purpose of enabling the connecting-sections to screw into the respective couplings, substantially as and for the 115 purpose described. 120

In testimony that I claim the foregoing as 125 my own I affix my signature in presence of witnesses.
